UNITED STATES PATENT OFFICE.

MOSES C. NIXON, OF CHICAGO, ILLINOIS.

WINDMILL.

Application filed December 17, 1917, Serial No. 207,485. Renewed May 15, 1922. Serial No. 560,864.

To all whom it may concern:

Be it known that I, MOSES C. NIXON, of the city of Chicago, in the county of Cook and State of Illinois, have invented certain new and useful Improvements in Windmills, of which the following is a specification.

This invention relates to windmills of the general type shown and described in my former Patent No. 1,246,008, issued November 6, 1917; and as the power transmitting mechanism and certain other features are not a part of the present invention they are not shown in this application; the object being to provide a pull-out mechanism for 15 operating the vane; and consists, preferably, in the construction hereinafter described.

In the drawings, Figure 1 is a side elevation of the supporting-frame and incasement of a windmill head, with present invention 20 attached, and Fig. 2 is a plan view of Fig. 1 with covering of incasement removed.

Referring to the drawings, similar numerals of reference indicate corresponding parts of the different views, in which 1 is 25 the supporting-frame, which in this case also forms the body of an incasement for power transmitting mechanism and a reservoir for lubricant, explained in my former patent, and 2 is a covering for the same. 30 This covering, which is preferably made of galvanized steel, is formed with an offset 2' so as to rest upon the body of incasement, is secured thereto, and extends downwardly over the same, so as to make the incasement more storm-proof. Said supporting-frame is mounted upon tubular mast 3 35 in position to swing about a vertical axis.

It being desirable that the incasement be as nearly dust and storm-proof as possible, 40 and that the pull-out mechanism be operative through the tubular mast, such a mechanism has been devised, which enters the mast through hub 4 of the supporting-frame and below the incasement. In the construction 45 shown, housing 5 is secured to lugs 6 that extend from hub 4, as by bolts 7, and revolvably mounted therein are sheaves 8 and 9, the former of said sheaves being so positioned as to extend through opening 10 in said hub. 50 Said housing may be formed so as to protect said opening and sheaves from the storm.

The vane-hinge 11 is pivotally mounted upon brackets 12 and 13, and the vane-stem 14 is rigidly secured to said hinge, is broken 55 off in the drawings, and the vane, which may be of the usual form, is not shown.

Around the vane-hinge pivot-pin 15 is placed torsion spring 16, which has a hook 17 at its upper end adapted to catch upon rib 18 of the vane-hinge. The lower end 60 of this spring is turned downward and adapted to enter hole 19 in tension piece 20. The tension piece is placed upon the vane-hinge pin and is provided with a rim 21, upon which the spring rests, and its hub 65 extends upwardly into the spring. At the upper end of this spring a rimmed collar 22 is provided, which, extends downward into the spring, the rim 23 being intended to prevent the collar from working too far 70 down. The object of this collar and the upwardly extending hub of the tension piece is to keep the spring centrally located as to the hinge-pin. From the side of the incasement extends a bracket 24, to which is 75 attached rod 25. Said rod passes through a hole in the arm of the tension piece and by the use of the nut 26 the tension on the torsion spring may be adjusted to meet requirements. From the lower part of the 80 vane-hinge is an extension 27, to which is secured chain 28, or other suitable connection, which passes partly around said sheaves, through opening 10 into and downward through the tubular mast, and is operated from below. In operation of the pull-out mechanism, the chain is drawn downward, thereby causing the vane to pivot and permitting the mill to become inoperative, and when released the torsion spring, or 85 other suitable mechanism, carries it back into normal position.

While this pull-out mechanism has been shown in connection with a windmill having a storm-proof incasement and the preferred 90 construction has been shown and described, I do not wish to be limited to either that type of windmill, as it is applicable to other types, or limited to the details shown as changes may readily be made without de- 95 parting from the spirit of my invention.

What I claim is:

1. In a windmill, the combination with a supporting frame provided with a hub, a tubular mast entering said hub upon which 100 said frame is mounted to swing about a vertical axis, an incasement, a vane pivotally mounted upon said frame, an opening in the side of the hub of said frame and extending into the tubular mast, a housing extending from said hub, sheaves mounted in 105 said housing, and means guided by said

sheaves and operative through said opening and mast without any connection through the incasement whereby the vane may be actuated.

5. 2. In a windmill, the combination with a supporting frame, of a tubular mast upon which said frame is mounted to swing about a vertical axis, an incasement, a vane pivotally mounted upon said frame, a housing supported upon said frame exterior to the incasement, means for swinging said vane at will which includes a connecting device which passes through the tubular mast without entering the incasement, and means contained within said housing for guiding said connection.

3. In a windmill, the combination with a supporting frame, a tubular mast upon which said frame is mounted to swing about a vertical axis, an incasement, a vane pivotally mounted upon said frame, a bracket

supported upon said frame exterior to the incasement, means for actuating said vane which includes a connecting device which passes through the tubular mast without 25 entering the incasement, and means carried by said bracket for guiding said connecting means.

4. In a windmill, the combination with a supporting frame, a tubular mast upon 30 which said frame is mounted to swing about a vertical axis, an incasement, a vane pivotally mounted upon said frame, and means for actuating the vane which includes a connecting device which passes through the 35 tubular mast without entering the incasement.

MOSES C. NIXON.
